[57] CLAIM

The ornamental design for the beverage display, as shown and described.

DESCRIPTION

FIG. 1 is a perspective view of a beverage display, showing mounted to a flat or corner of a wall disclosed in phantom line;

FIG. 2 is a front view thereof;

FIG. 3 is a back view thereof;

FIG. 4 is a left side view, the right side view being a mirror image thereof;

FIG. 5 is a top plan view; and,

FIG. 6 is a bottom view thereof.

The broken lines are shown for illustrative purposes only and form no part of the claimed design.
